UNITED STATES PATENT OFFICE.

CHARLES W. REYNOLDS, OF ADRIAN, MICHIGAN.

SIDE-HILL PLOW.

1,292,514.

Specification of Letters Patent. Patented Jan. 28, 1919.

Application filed May 15, 1918. Serial No. 234,616.

To all whom it may concern:

Be it known that I, CHARLES W. REYNOLDS, a citizen of the United States, residing at Adrian, in the county of Lenawee 5 and State of Michigan, have invented new and useful Improvements in Side-Hill Plows, of which the following is a specification.

This invention comprehends generally improvements in that class of inventions known as plows and more particularly has reference to a side hill plow.

It is the primary aim and object of the present invention to provide a device of the above character wherein improved means is employed for connecting the main beam to the auxiliary beam between the double-ended plow so as to permit the operator to readily and easily control the plow while turning 20 the beam.

It is an equally important object of this invention to provide a device of the above character wherein the main beam is designed so that a portion thereof overlies the supplemental beam and is capable of being removably locked thereto subsequent to the turning of the main beam in either direction, thus preventing relative movement of the beam when the plow is in use.

More particularly the present invention embraces the provision of manually actuatable means on the main beam for removable engagement with the respective ends of the auxiliary beam to prevent accidental relative movement between the beams said means being positioned in proximity to the handles so as to be easily actuatable when it is desired to turn the beam.

As a further improvement this invention 40 contemplates the provision of the improved double-ended plow designed so as to be readily supported to assure of the effective operation thereof and also designed so that the mold board near one end will not engage 45 roots when the other end of the plow is in operation.

Among the other aims and objects of this invention may be recited the provision of a device of the character described with a view 50 to compactness, and in which the number of parts are few; the construction simple, the cost of production low and the efficiency high.

Other improvements and novel details in 55 the construction and arrangement of the various parts of the apparatus will be brought

out more in detail in the description to follow, which for a clear understanding of the invention should be considered in connection with the accompanying drawings forming a 60 part hereof, and wherein is disclosed for the purpose of illustration a convenient and satisfactory embodiment of the invention. It is to be noted in this connection that minor changes in the construction and arrangement 65 of parts may be made without departing from the principle of operation of the various parts.

The invention is clearly illustrated in the accompanying drawings, in which:— 70

Figure 1 is a front elevation of the invention partly in longitudinal section;

Fig. 2 is a top plan view of the same;

Fig. 3 is a side elevation of the invention;

Fig. 4 is a transverse section taken on line 75 4—4 of Fig. 1;

Fig. 5 is an elevation of the invention illustrating the position assumed when the device is being turned;

Fig. 6 is a fragmentary longitudinal section detail. 80

Similar characters of reference are employed in all the above described views, to indicate corresponding parts.

Referring now, more particularly, to the 85 accompanying drawings, there is provided a double-ended plow which in the present instance may be said to consist of opposed plow shares 1 the outer ends of which terminate in points 2 while mold boards 3 extend upwardly from the shares being secured thereto through the instrumentality of braces 4. A land-side bar 5 has its respective ends formed integral with shares 2. Standards 6 are formed at their lower end 90 with shoes 7 which are rigidly secured to the land side bar by fastening devices 8 while braces 9 are employed and are connected between the shoes and the mold boards to increase the rigidity of the parts relative to 95 each other. A supplemental beam 10 connects the upper ends of the standards and is formed with a central transverse opening 11 and also with openings 12 near the respective ends thereof. 100

A sectional main beam indicated in its entirety by the numeral 13 is now employed and embodies a main section 14 and an auxiliary section 15 disposed above the main section and projecting longitudinally therefrom. This section may, if desired, be formed of wood and is preferably connected 110

to the main section through the instrumentality of a plate 16 disposed on top of the section 15 and secured to the section 14 by means of a nut and bolt arrangement 17. 5 This plate is bent intermediate its ends to form a sleeve 18 for a purpose that will presently appear. In connecting the main section 14 to the supplemental beam 10 a king bolt 19 is passed centrally through the 10 main section 14 and the opening 11 the head of the bolt resting on a washer 20 which is disposed above the main section and engaged by the bolt. Suitable resilient means such as a coil spring 21 is now arranged 15 about the lower projecting end of the king bolt and has its upper end bearing against the upper surface of the supplemental beam 10 and against the washer 22, which is disposed about the bolt and retained against 20 displacement by a retaining nut 23 also adjustably mounted on the bolt and particularly adapted for governing the tension of the spring. The spring of course serves to 25 yieldingly hold the main section 14 in intimate contact with the upper surface of the supplemental beam and facilitates the relative turning of the main beam and the supplemental beam. In order to guide the device a block 24 is disposed on the upper surface of the main section 14 adjacent the opposite end thereof. Handle bars 25 are secured through the instrumentality of suitable fastening devices 26 on opposite sides of the block and are braced with respect to 30 each other by means of cross bars 27. In assuring of the retention of the block in position and also the bracing of the handle bars an ear bolt 28 is passed through the plate 29 which is disposed on top of the block and 35 through the main section 14 being retained by means of a nut 30. A key bolt has its shank 31 passed through the plate 29 and the section 14 while the wings 32 thereof are straddled about the plate and embrace the 40 inner ends of the handle bars while a nut 34 serves to prevent accidental displacement of the shank of the key bolt.

As intimated, improved means have been 45 employed for preventing accidental turning movement of the main and auxiliary beams with respect to each other. In reducing this feature of the invention to practice a hand lever 35 is pivotally mounted by means of a pin 36 between the ears of the 50 bolt 28 and has its outer end pivotally mounted by means of a suitable fastening device 37 to a link 38 which depends therefrom. This link is formed with a slot 39 which is engaged by a pintle 40 supported 55 in turn between the spaced ears 41 of the plate 29, the pintle serving to guide and limit the movement of the link. A pin projection 42 depends from the lower end of 60 the link and is engaged in an opening 43 in the main section 14 and also in either

one of the openings 12 in the supplemental beam. Coöperating with the pin projection in preventing relative movement of the main and supplemental beams is a U-shaped retainer 44 embodying an intermediate portion 70 45 and side arms 46. The side arms are engaged by a bolt 47 which is journaled for swinging movement in the sleeve 18 while the intermediate portion is adapted to be engaged beneath the adjacent end of the 75 supplemental beam. In actuating the retainer an actuating rod 48 has its inner looped end 49 loosely engaged in an ear 50 formed integral with one of the side arms 46. This rod is formed near its opposite 80 end with a series of notches 51 designed for engagement with an eye 52 depending from one of the handle bars and through which the rod is slidably mounted. A hand grip 85 53 is formed on the outer end of the rod in a position beneath one of the handle bars to facilitate sliding of the rod through the eye and consequently swinging the retainer in a corresponding direction. It is apparent that when the inner notch is engaged in 90 the eye the retainer will be embraced or straddled about both of the beams but upon inward pushing of the rod so that the outermost notch will engage the eye the retainer will be swung forwardly and from engagement with the supplemental beam. When in 95 this position it is only necessary to depress the hand lever 35 and swing the horizontal main beam upon the supplemental beam. This action occurs when the operator reaches 100 one end of the field and desires to plow in the opposite direction. By the provision of the double-plow and the turnable main beam the operator is thus enabled to turn the beam and subsequently lock the parts in substantially rigid position and thus use the other end of the plow without experiencing the usual difficulty in turning the plow itself.

With a view toward constructing the double-ended plow so that it will at all times 110 be maintained in a properly supported position and so that it will not engage roots, etc. during plowing action, a substantially U-shaped guarding and supporting member 115 54 is employed in the present instance consisting of an intermediate portion 55 and side arms 56 which are connected as at 57 to the inner ends of the adjacent plow shares in such a manner that the intermediate portion will be arranged longitudinally of the 120 device and near the lower outer edges of the shares as indicated. This member of course serves to coöperates with the land side bar in supporting the double-ended plow and prevents the roots and the like from being 125 engaged beneath the plow shares as is apparent.

In order that the device may be propelled a draft clevis 58 is mounted on the outer end 130 of the section 15 of the main beam.

It is believed that in view of the foregoing description a further detailed description of the operation of the invention is entirely unnecessary. Likewise it is believed that the 5 advantages of the invention will be readily apparent.

As many changes could be made in the above construction and many apparently widely different embodiments of this invention 10 could be made without departing from the scope thereof and it is intended that all matter contained in the above description or shown in the accompanying drawings shall be interpreted as illustrative and not in a 15 limited sense. It is also to be understood that the language used in the following claims is intended to cover all the generic and specific features of the invention herein described and all statements of the scope of 20 the invention which as a matter of language might be said to fall therebetween.

Having thus clearly described the invention what is claimed as new and desired to be secured by Letters Patent is:—

25 1. The combination with a double-ended plow embodying a supplemental beam having openings adjacent the respective ends thereof, of a main beam turnably connected above the supplemental beam and formed 30 near one end with an opening, a vertically slidable link on the main beam, a pin projection depending therefrom and positioned in the opening in the main beam and designed for engagement with the opening in either 35 end of the supplemental beam, a manually operable lever operably connected to the link, a retainer swingingly mounted near the opposite end of the main beam for embracing the adjacent end of the supplemental 40 beam for coöperating with the pin projection in preventing accidental turning movement of the main beam, and means for actuating the retainer.

2. The combination with a double-ended 45 plow embodying a supplemental beam having a central opening therein and having other openings formed near its respective ends, of a main beam formed with a central opening and normally resting above the supplemental beam, a king bolt passing centrally through the central openings for turnably connecting the beams, a coil spring disposed about the bolt for tensioning the beams with respect to each other, a nut 50 engaged on the king bolt for adjusting the

tension of the spring, and coöperative manually operable means mounted on the respective extremities of the main beam for removable engagement with the adjacent ends of the supplemental beam for preventing accidental turning movement of the beams with respect to each other. 60

3. A side hill plow including a pair of opposed plow shares, mold boards connected thereto, a land side bar integral at its respective extremities with the shares, a guarding and supporting member connected to the shares near the outer edges thereof, standards connected at the lower ends of the land side bar, means for bracing the shares 70 with respect to the standards and with respect to the mold boards, a supplemental beam connected to the upper ends of the standards, a main beam turnably connected to the supplemental beam and coöperative 75 manually operable means mounted on the respective ends of the main beam for removably locking the main beam to the adjacent ends of the supplemental beam to prevent accidental relative movement of the beam. 80

4. The combination with a supplemental beam of a double-ended plow, of a main beam turnably connected to the supplemental beam, a block disposed above one end of the main beam, handle bars connected 85 upon opposite sides of the block, a plate disposed above the block, spaced ears formed on the inner end of the plate and projecting beyond the block, an ear bolt for fastening the plate and the block to one end of the 90 main beam, a key bolt for facilitating the fastening of the plate and the block to the beam and for bracing the inner ends of the handle bars, a link slidably mounted between the ears of the arm, a pin projection depending 95 from the link and slidably mounted through the main beam and removably engageable with either end of the supplemental beam, a hand lever pivotally connected to the link for releasing the pin projection, a U-shaped 100 retainer swingingly connected to the beam near the other end thereof and designed to embrace the adjacent end of the supplemental beam for coöperating with the pin projection in preventing relative turning of 105 the beams, an actuator rod for adjusting the retainer, and means for holding the actuating rod in various positions of adjustment.

In testimony whereof I affix my signature.

CHARLES W. REYNOLDS.
